(57) **CLAIM**

The ornamental design for a motorcycle brake rotor, as shown and described.

DESCRIPTION

FIG. 1 is a front, right perspective view of a first embodiment of a motorcycle brake rotor showing our new design; FIG. 2 is a front elevation view thereof; FIG. 3 is a rear elevation view thereof; FIG. 4 is a right elevation view thereof; FIG. 5 is a left elevation view thereof; FIG. 6 is a top plan view thereof; and FIG. 7 is a bottom plan view thereof.

FIG. 8 is a front, left perspective view of a second embodiment of a motorcycle brake rotor showing our new design; FIG. 9 is a front elevation view thereof; FIG. 10 is a rear elevation view thereof; FIG. 11 is a right elevation view thereof; FIG. 12 is a left elevation view thereof; FIG. 13 is a top plan view thereof; and, FIG. 14 is a bottom plan view thereof.

The broken lines in the drawing represent portions of the motorcycle brake rotor that form no part of the claimed design.
